APPLIANCE FOR MENDING LADDERS

Filed July 17, 1947

UNITED STATES PATENT OFFICE

2,532,409

APPLIANCE FOR MENDING LADDERS

Olga Joho, Basel, Switzerland

Application July 17, 1947, Serial No. 761,497
In Switzerland August 8, 1946

9 Claims. (Cl. 66—117)

1

Needles for mending ladders in knitted textures are known in various types, but for one reason or another cannot satisfy the requirements; they being especially unsuitable for mending fine ladies' stockings, because the needle must work reliably for this purpose.

The mender according to the invention is distinguished from these well-known devices by a hollow shank having a hooked forward end and a spring-biassed cam by means of which the hook can alternately be opened and closed, said cam being provided with a recess which is entered by the pointed end of the hook when closing.

The accompanying drawing illustrates by way of example three preferred forms of embodiment of the invention.

Fig. 1 is a lateral view of the first form,

Fig. 2 is corresponding partial longitudinal section,

Fig. 3 represents a fragmentary top view seen in the direction of the arrow III of Fig. 2,

Fig. 4 shows a cross-section taken on the line IV—IV of Fig. 2,

Fig. 5 is a modified form of the slide member,

Fig. 6 shows a cross-section on the line VI—VI of Fig. 5,

Figs. 7 to 10 shows the manipulation and action of the appliance in different stages of ladder mending,

Fig. 11 represents a partial longitudinal section and a partial lateral view of the second form of embodiment,

Fig. 12 is a top view of the mender shown in the direction of the arrow XII of Fig. 11,

Fig. 13 shows a longitudinal section of the front portion of the mender according to the third form,

Fig. 14 shows an enlarged detail section taken on the line XIV—XIV of Fig. 13, and

Fig. 15 is a lateral view of detail indicated in Fig. 14.

Referring to Figs. 1 to 4, numeral 1 designates a tubular shank whose forward end is shaped to form a hook 2. Two lateral stepped guide faces 3 lead from hook 2 to the cylindrical portion of the shank. The shank 1 has attached to its rear end a bail 4 serving as a handle. Embedded in shank 1 is the cylindrical slide 5 connected to said bail 4 by a pull spring 6. Mounted on the slide 5 is a cross-pin 7 engaging a guiding slot 8 provided in an auxiliary web 9 of the bail 4 to hold the slide member 5 against rotation in shank 1, the guide slot limiting at the same time a longitudinal displacement of said slide in the shank 1. At its fore-part the slide 5 is so

2

shaped as to form a cam 10, whose rearwardly sloped face 11 serves to confine an upper depression on the side obverted to the cam. At the front end the cam 10 goes through a guiding face 12 over in a tongue 13 forming the forward pointed end of the slide member. An intermediate longitudinal groove subdivides the cam in two equal portions between which the hook 2 enters with its free end, if the slide 5 is correspondingly displaced lengthwise on shank 1. The pull spring 6 tends to keep the slide 5 in the retracted position as in Fig. 2, in which the rear confining face 11 of the depression (of slide 5) adjacent the cam registers with the two lateral guide faces 3 on shank 1.

The manipulation and action of the afore-described appliance is apparent from Figs. 7 to 10. These figures exhibit a portion of a loop structure between the vertical loop rows 15 and 16 thereof a ladder 17 can be seen. To mend this, the point of the shank is as in Fig. 7 passed through the loop 18 of the still existing top stitch of the ladder 17, i. e. so far, until the loop 18 comes to lie behind the cam 10 in the depression formed by the two sloped faces 11 and 11'. Now the mender is withdrawn in the direction of the arrow A in Fig. 8, whereby the uppermost cross thread 19 of the ladder 17 becomes engaged by the open hook 2 and is carried off. As then the shank can be withdrawn further, as in Fig. 9, the cam 10 dwells momentarily in its position relative to the loop 18, since the loop lying behind the cam 10 retains the same and prevents its regression. Thereby the cam 10 becomes displaced towards the open end of the hook, the latter eventually entering the recess 14 on cam 10 to close the hook. Upon further withdrawal of the shank 1 the loop 18 finally slips over the closed hook, while the former cross thread 19 has been drawn out to form a fresh loop 19'. The shaft is then again passed forwards through the loop 19', to cause this to slide over the cam 10 into the notch or depression behind the same (Fig. 7). The lift of the next loop is thereafter accomplished in the same way as described.

In the modified form, as in Figs. 5 and 6, the slide member 5 is of channeled cross-section to form the longitudinal groove 14 which in the use of the appliance permits temporary reception of the hook 2 between the two portions of the cam 10'. The rear guide face 11 of the cam 10' is curved so as to form a corner together with the adjacent confining face 11' of the upper depression of the slide members 5, in which corner, on moving the needle, the taut thread is each time

received by the said depression, to withhold it to a certain extent to prevent its premature slipping off the cam 10', which must only take place when the hook has caught another thread; the slide member can be drawn through the taut thread against the action of its spring to close the hook. In this form of embodiment the forward guide face 12 of the cam 10' extends stepless and evenly towards the underside of the slide member to form a pointed portion therewith.

Also in this case a shank of channeled cross-section is provided to guide the slide member. In addition the shank has two lateral guide faces leading from the hook to the body proper, said faces being adapted to the run of the forward guide face 12 of the cam 10' of slide 5, i. e. they are stepless.

In the form of embodiment according to Figs. 11 and 12, numeral 1 again denotes the shank with the hook 2, the shank being of channeled cross-section. Contrary to the forms as per Figs. 1 to 3 the hook is not rounded in a semicircular way but first extends straight at an inclination and is then bent back at an acute angle α (Fig. 11) with respect to the lower edge of the shank to terminate in a pointed end portion 2a lying parallel to the longitudinal axis thereof. This design of the hook allows of a very smooth and rapid slipping of the loop from the hook. In this embodiment the cam 10² is formed by a latch accommodated in the hollow space of the shank and rockable about an axis 20 extending transversely to the plane of the hook. A recess 14 of the latch is adapted to receive the pointed end of the hook when closing.

The shank is in axial direction displaceably supported in a holder 21 and is fitted with three notches or rests 22, 23 and 24, said holder 21 including a set screw 25 for selective engagement with one of the rests 22 to 24. Numeral 26 marks a pull spring arranged inside the holder 21 and wound round the rear end of the shank, being anchored at one end (27) in the holder 21, and at the other end secured to the latch 10². Said spring tends to keep the latch 10² in the open position as shown in Fig. 11. By axially displacing the shank 1 in holder 21 the tension of said spring 26 may be varied within wide limits. When the set screw 25 engages the rest 24, then the spring tension is greatest and the mending appliance can be used for narrow, coarse and strongly knitted ware. If, on the other hand, the screw 25 is set in rest 22, the spring tension is at its lowest which allows the mender to be utilized preferably for fine knitted ware. The intermediate rest 23 is used for mending cotton and coarse knitted silk stockings. For the remainder the manipulation and action of this appliance is the same as disclosed with reference to Figs. 1 to 10.

In the third form of embodiment according to Figs. 13 to 15, numeral 1 again designates the shank, 2 the hook, and 10³ the latch that is rockable about the axis 20.

In contradistinction to the example as per Figs. 11 and 12, in the form according to Figs. 14-15, a plate spring 28 is provided for rocking the latch into the open position. This plate spring is at one end fixed in the latch 10³ and bears at the other end against an abutment 29 of a holding bail whose springy limbs 30 embrace the shank 1 laterally. The holding bail is longitudinally movable relative to the shank and may be arrested in various positions. To this end the two limbs 30 of the holding bail are each on their inner surfaces, with a projection 31 adapted to co-

operate with the rests 32, 33 and 34 arranged in the shank.

The plate spring 28 is most taut on locking the holding bail in the rests 32, while the spring is taut at its lowest when the projections 31 engage the rests 34. The rests 33 correspond to a medium spring tension. For the remainder the manipulation and action of the appliance is the same as with the forms previously described.

10 Instead of being round or channeled, the shank may be for instance, of oval or angular (three, four and more angled) cross-section. The slide is given a cross-section such as to permit of its easy working in the shank; with angular cross-section of the shank, the slide may, instead of being conformed in shape, also be of circular cross-section. In every case due provision will of course be made to hold the slide member from rotating relative to the shank; for this the slide 20 may, for instance, be fitted with a lateral wing or may have two such wings passing on opposite sides of the shank through guide slots so dimensioned as to limit at the same time the displacement of the slide member. Alternatively, the 25 latter member may be located for instance, in a cylindrically shaped handle instead of a lateral one. Instead of a pull spring, the slide member may also be loaded by an expansion spring mounted conveniently into the device and tending 30 to keep the slide member in its retracted or rest position.

If required a limited displaceable and spring-biassed sleeve may be arranged on the shank to serve as an abutment for the ware to be mended 35 to limit the protrusion of the appliance by means of the edge of the desirably enlarged front end of said sleeve.

Being of comparatively simple and cheap design, the aforescribed mending appliance permits of reliable working with but little effort.

What I claim is:

1. In an appliance for mending ladders of ladies' stockings, the combination of a hollow shank having at one end a hook; a cam mounted 45 in said shank to close and open said hook, alternatively, said cam being designed as a latch rockable about an axis extending transversely of the plane of the hook; and a spring connected to said cam for adjustably biasing said cam.

50 2. A mending appliance according to claim 1, in which said shank is of channeled cross-section, the latch being located in said hollow space thereof.

55 3. A mending appliance according to claim 1, having a holder in which said shank is axially displaceable and arrestable in various positions with respect to the holder and said spring being a pull spring which has one end anchored to said holder and the other end secured to said latch, 60 so that the tension of said spring may be varied selectively by axially displacing the shank in said holder.

65 4. An appliance according to claim 1 in which the spring is a leaf spring one end of which is fixed to said latch, and an abutment against which bears the other end of said spring, said abutment being adjustably mounted in said shank to adjust the tension of said spring.

70 5. An appliance according to claim 1 in which said latch is rockable through an angle of less than 90°.

6. An appliance according to claim 1 in which said cam has a convex surface concentric with said axis.

75 7. In an appliance for mending ladders of

ladies' stockings, a hollow shank having a hook at one end including a portion extending forwardly and upwardly at an obtuse angle to the shank and another portion extending rearwardly from said first portion and defining an acute angle therewith, a cam latch mounted in said shank rearwardly of and adjacent said hook and adapted to close and open said hook alternatively, said cam latch having a recess in alignment with the end of the hook and adapted to receive the same when the cam latch is closing, means mounting the cam latch for rocking movement about an axis transverse to the shank and the hook, a biasing spring connected to the cam latch, and means for adjusting the tension of said spring to adjustably bias the said cam latch.

8. An appliance as defined in and by claim 7 including a holder in which the shank is longitudinally slidably mounted, a spring secured at one end to the cam latch, coiled around a portion of the shank and anchored to the holder, said shank having a plurality of spaced notches therein and a set screw threaded through said holder and engageable in any of said notches whereby the shank can be longitudinally displaced relative to said holder and fixed in said displaced position to adjust the tension of said spring to adjustably bias said cam latch.

9. An appliance as defined in and by claim 7 in which said shank is channel-shaped, a leaf

10
15

25

30

spring fixed at one end to the cam latch and disposed within the shank, an inverted longitudinally slideable U-shaped bail straddling said shank, an abutment depending from the central portion of said bail and bearing against said spring, said shank having longitudinally spaced indentations therein and the legs of said bail having projections in the inner surfaces thereof engageable with the indentations to hold said bail in longitudinally adjusted positions to adjust the tension of said spring to adjustably bias said cam latch.
